CIRCUIT BREAKER

Harold G. Baxter, Wilkinsburg, Pa., assignor to
 Westinghouse Electric & Manufacturing Company, East Pittsburgh, Pa., a corporation of Pennsylvania

Application December 2, 1941, Serial No. 421,301

19 Claims. (Cl. 200—116)

This invention relates to circuit breakers and more particularly to circuit breakers of the type which are manually operable to open and close the circuit and operable automatically to open the circuit in response to predetermined conditions.

An object of the invention is to provide an improved circuit breaker having a pair of pivoted contact members which cooperate one with the other to close a circuit, each contact member being operable independently of the other to interrupt the circuit.

Another object of the invention is the provision of an improved circuit breaker having a pair of cooperating contact means and a mechanism which is manually operable to move one of the contact means to open and to close the circuit, and having current responsive trip means operable to cause movement of the other contact means to an open position to automatically open the circuit in response to predetermined overload conditions.

Another object of the invention is to provide an improved circuit breaker having a pair of co-operating contacts and a mechanism which is manually operable to cause movement of one of the contacts to open and to closed position with a snap action, and having current responsive trip means operable to cause movement of the other contact to an open position to automatically open the circuit in response to predetermined overload conditions.

Another object of the invention is the provision of an improved circuit breaker having a pair of cooperating contact means and a mechanism which is manually operable to move one of said contact means to open and to close the circuit, and having current responsive trip means operable to cause movement of the other contact means to an open position to automatically open the circuit in response to predetermined overload conditions, said other contact means being manually moved to a closed position by operation of the mechanism to open position.

Another object of the invention is the provision of a circuit breaker having an operating mechanism operable by a manual operating handle to open the contact means and which will reclose the contact means upon release of the handle, and having current responsive trip means operable to cause automatic opening of the contact means irrespective of the position of the mechanism or handle.

Another object of the invention is the provision

of a circuit breaker having an operating mechanism operable by a manual handle to close the contact means and which will open the contact means upon release of the handle, and having a current responsive trip means operable to cause automatic opening of the contact means irrespective of the position of the operating handle and independently thereof.

Another object of the invention is the provision of an improved circuit breaker which is simple, safe and reliable in operation and which is inexpensive to manufacture.

The novel features that are considered characteristic of the invention are set forth in particular in the appended claims. The invention itself, however, both as to structure and operation, together with additional objects and advantages thereof, will be best understood from the following description of a single embodiment thereof when read in conjunction with the accompanying drawings in which:

Fig. 1 is a vertical sectional view through a circuit breaker embodying the principles of the invention, taken substantially on line I—I of Fig. 5 and showing the breaker in the manually opened position.

Fig. 2 is a view similar to Fig. 1 but showing the breaker in the closed position.

Fig. 3 is a view similar to Fig. 1 but showing the breaker in the automatically tripped open position.

Fig. 4 is a vertical sectional view through the breaker similar to Fig. 1 but showing the overcenter spring adjusted to bias the manual operating lever and the manually operable contact arm to the open position.

Fig. 5 is a vertical transverse sectional view through the breaker taken substantially on line V—V of Fig. 1, and

Fig. 6 is a vertical sectional view similar to Fig. 1 but showing the overcenter spring adjusted to bias the manual operating lever and the manually operable contact arm to closed position. In Fig. 6 the breaker is normally closed and when opened manually will automatically reclose when the manual operating lever is released.

Referring to the drawings, particularly to Fig. 2, the circuit breaker is of the single pole type and comprises, generally, a base 11 of molded insulating material, a removable cover 13 also of molded insulating material, a U-shaped manual operating lever 15, a switch arm 17 operable by the operating lever 15, a pivoted contact lever 19, an arc extinguisher 21, a trip device 23 and

terminals 25 and 27 for connecting the breaker in an electrical circuit.

The U-shaped operating lever 15 comprises a pair of parallel levers pivotally supported at their inner ends on a pivot pin 29 mounted in the side walls 31 of the base 11 and joined at their outer ends by a yoke 33 (Fig. 5). A manual operating handle 35 of insulating material is suitably secured to the yoke 33 of the lever 15 and projects through a slot 37 in the cover 13.

The switch arm 17 comprises a pair of parallel arms of conducting material pivotally supported on pivot studs 39 projecting inwardly from each of the side walls 31. At their free ends the switch arms 17 are provided with inwardly formed ears 41 to which is secured, by rivets or other suitable fastening means, a contact member 43.

An overcenter spring 45 has one end hooked through an opening in a projection 47 on the yoke 33 of the operating lever 15, and the other end hooked over a pin 49 secured to and extending between the arms 17.

Limit stops comprising studs 51 and 53 mounted in the side walls 31 of the base are provided to limit respectively the clockwise and counter-clockwise travel of the operating lever 15.

The contact lever 19, which is of conducting material, is in the form of a bell crank and is pivotally mounted at a point near its apex on a pivot comprising a bolt 55 mounted in bosses 57 moulded integral with the base 11. Suitable openings are countersunk from the outside of the base to receive the head of the bolt 55 and a nut 59 (Fig. 5) which secures the bolt in place.

One arm 61 of the contact lever 19 carries a contact 63 which in the closed position of the breaker cooperates with the contact 43 to complete the electrical circuit through the breaker.

The other arm 65 of the contact lever 19 has secured thereto a bar 67 of insulating material, and the bar 67 carries a latch member 69 which cooperates with the trip device 23 to releasably restrain the contact lever 19 in the closed circuit position shown in Fig. 2. A spring 71 coiled about the pivot 55 has one end bearing against the base 11 and the other end bearing against the arm 61 of the contact lever 19 to bias the latter in a clockwise or contact opening direction.

The trip device 23 comprises a bimetal element 73 rigidly secured to the formed over inner end of the terminal 25, and this bimetal element at a point near its free end carries a latch 75 which cooperates with the latch member 69 to releasably restrain the contact lever 19 in closed position. The free end of the bimetal element 73 is electrically connected to the arm 65 of the contact lever 19 by means of a flexible conductor 77 the terminals of which are secured respectively to the bimetal element and the arm 65 by screws 79 and 81. The switch arm 17 is electrically connected to the inner end of the terminal 27 by means of a flexible conductor 83. The conductor 83 is secured to the terminal 27 by a screw 85 and is crimped to the switch arm 17 at 87 thus completing the electrical circuit through the breaker which circuit may be traced from the terminal 25 through the bimetal element 73, the flexible conductor 77, contact lever 19, the contacts 63 and 43, switch arm 17, and the flexible conductor 83 to the terminal 27.

The arc extinguisher 21 may be of any suitable type, preferably of the slotted magnetic plate type in which the arc drawn by rupture of the current is drawn into the extinguisher and broken

up into a plurality of short arcs and quickly cooled and extinguished.

The circuit breaker is manually operated to open the contacts by rotating the lever 15 in a counter-clockwise direction from its Fig. 2 position to the Figure 1 position. As the lever 15 is rotated the line of action of the overcenter spring 45 passes to the left of the center line 39-49 and exerts a force which biases the switch arm 17 in a clockwise or circuit opening direction. As soon as this occurs the switch arm 17 is moved to its open position with a snap action, its movement in opening direction being limited by striking the pivot 29.

When the switch arm 17 is in its fully opened position (Fig. 1) the line of action of the spring 45 is to the left of a line drawn from the center of the pivot 29 and the point of attachment of the spring to the ear 47 thus biasing the lever 15 in its "off" position against the limit stud 53. The parts will remain in this position until the manual lever 15 is manually rotated clockwise toward its "on" position. During the clockwise movement of the lever 15 the line of action of the spring 45 passes to the right of the line 39-49 causing the switch arm 17 to rotate to its closed position with a snap action. In the closed position of the lever 15 and switch arm 17 the spring 45 biases these parts to their closed positions.

The breaker is tripped open automatically by the trip device 23 in response to an overload current of greater magnitude than that for which the breaker is rated. The bimetal element 73, which is connected in series relation in the circuit controlled by the breaker, is heated by excessive current flowing therethrough, and when heated a predetermined amount its free end flexes toward the left (Fig. 3) causing the latch 75 to free the contact lever 19, whereupon the spring 71 acts to rotate the contact lever 19 clockwise about its pivot 55 thereby moving the contact 63 to open position away from the contact 43. The clockwise movement of the contact lever 19 is limited by the insulating bar 67 striking an angular member 89 rigidly secured to a cross bar 91 connecting the levers forming the manual operating lever 15. When the contact lever 19 is rotated clockwise the spring 45 rotates the switch arm 17 slightly counterclockwise until it is arrested by striking the limit stop 51.

After the breaker has been tripped open automatically the contact lever 19 must be reset before the contacts can be closed. Resetting is accomplished by manually operating the operating lever 15 counterclockwise to the "off" position. Movement of the lever 15 counterclockwise to the "off" position rotates the contact lever 19 also counterclockwise by means of the angular member 89 to relatch the latch member 69 with the latch 75 on the bimetal element. Movement of the lever 15 to the "off" position (Fig. 1) also moves the spring 45 overcenter and causes the switch arm 17 to move to its open position shown in Fig. 1. The contacts can then be closed by movement of the manual operating lever 15 to its "on" position in the previously described manner.

It is frequently desirable, in test circuits and control circuits, to provide switches which are normally open but which may be momentarily closed manually by an operating handle and which, upon release of the handle, will automatically reopen. Also it is desirable to provide in such circuits, switches which are normally closed but which may be opened momentarily by a man-

ually operable handle and which upon release of the handle will automatically reclose.

One of the important features of the instant invention is to provide a circuit breaker which functions as a conventional circuit breaker which is operable manually to open and close the circuit and operable thermally in response to overload currents to automatically open the circuit and which, by a simple adjustment, can be made to function in the manner set forth in the preceding paragraph. This is accomplished by providing a plurality of points of anchorage for the overcenter spring 45 to the switch arm 17. One of these points is so located that the operating lever 15 is always biased to its "off" position, and the other point is located so that when the spring 45 is attached thereto the lever 15 is biased to its "on" position.

Referring to Fig. 4, the overcenter spring 45 may be attached to the contact arm 17 at any one of three points designated as the pin 49, a pin 49a, and a pin 49b. In Fig. 4 the spring 45 is shown attached to the pin 49a and normally biases the switch arm 17 clockwise to its open position, and biases the operating lever 15 counter-clockwise to its "off" position. Movement of the operating lever to its "on" position moves the line of action of the spring 45 to the right of the line 39-49a causing the contact arm to move counterclockwise to its closed position with a snap action. However, with the lever 15 in its "on" position and the switch arm 17 in the closed position, the spring 45, tensioned between 41 and 49a does not move overcenter to the right of the line 29-47 and, therefore, continues to bias the operating lever 15 in a counterclockwise direction. Consequently, upon release of the handle 35, the spring 45 moves the lever 15 to its "off" position. During this movement, the line of action of the spring passes to the left of the line 39-49a which results in moving the switch arm 17 to its open position.

Referring now to Fig. 6 it may be seen that the spring 45 has its inner end hooked over the pin 49b. The parts are shown in Fig. 6 in their open position and it can be observed that, in the fully open position, the line of action of the spring 45 remains to the right of the line 29-47 and thus biases the operating lever 15 to its "on" position. When the handle 35 is released and the spring 45 moves the lever 15 clockwise, the line of action of the spring 45 passes to the right of the line 39-49b whereupon the switch arm 17 is moved to close the contacts with a snap action. According to the adjustment of the spring 45 as shown in Fig. 6, the operating lever 15 is normally biased to its "on" position and the switch arm 17 is normally biased to its closed position, and after being opened manually will automatically return to closed position when the handle 35 is released.

From the foregoing description it can be seen that the invention provides a circuit breaker which is both manually and automatically operable to interrupt a circuit, and wherein two pivotally mounted contact members are movable each independently of the other, one being operable to interrupt the circuit in response to overload currents, and the other being manually operable to interrupt or close the circuit. It may be further observed that a simple adjustment has been provided whereby the breaker can be arranged to automatically close after having been opened manually, or whereby the breaker will automatically open after having been closed man-

ually and the operating handle is released. In all cases the breaker is automatically operable to open the circuit in response to an overload, irrespective of the position of the manual operating handle.

Having described the invention in accordance with the patent statutes, it is to be understood that various changes and modifications may be made in the structural details disclosed without departing from some of the essential features of the invention. It is, therefore, desired that the language of the appended claims be given as reasonably broad interpretation as the prior art permits.

15 I claim as my invention:

1. A circuit breaker comprising a switch member, operating mechanism for said switch member comprising an operating member movable to an open position and to a closed position, and spring means operatively connecting the switch member and the operating member to cause movement of said switch member to an open position and to a closed position, said switch member being mounted for movement independently of said operating member, a contact member cooperating with the switch member and biased open, and current responsive means for releasably restraining said contact member in cooperative relation with the switch member, said current responsive means being operable in response to overload current to release said contact member.

2. A circuit breaker comprising a switch member, operating mechanism for said switch member comprising a manually operable member and resilient means connecting said manually operable member to the switch member for moving said switch member to open and closed positions, with a snap action, a contact member cooperating with the switch member to complete an electrical circuit, means biasing said contact member in opening direction, and electroresponsive means for releasably restraining the contact member in closed position, said electroresponsive means being operable in response to predetermined conditions to release the contact member.

3. A circuit breaker comprising a switch member, operating mechanism comprising a member movable to open and to closed positions and an overcenter spring connecting said operating mechanism to said switch member for moving said switch member to open and closed positions, a pivoted contact member cooperating with said switch member, means biasing the contact member for movement in an opening direction away from said switch member, and a bimetal element for releasably restraining said contact member in a closed position, said bimetal element being operable when heated a predetermined amount to release the contact member.

4. A circuit breaker comprising a movable switch member, a manual member movable to an open position and to a closed position, an overcenter spring connecting said manual member to said switch member and operable upon movement of the manual member to move the switch member to open and closed positions, a releasable contact member biased open, and current responsive means for releasably restraining said contact member in engagement with the switch member when the manual member is in closed position, said current responsive means being operable in response to overload currents to release the contact member.

5. A circuit breaker comprising a pivoted switch member biased to closed position, a pivoted contact member biased to open position, an operating member biased to a closed position and operable to an open position to cause movement of the switch member to open position, said switch member being mounted for movement independently of said operating member, and a trip device operable in response to predetermined circuit conditions to cause automatic movement of the contact member to open position.

6. A circuit breaker comprising a pivoted switch arm, operating mechanism for said switch arm comprising an operating member and an overcenter spring connecting said operating member to the switch arm, said operating member being operable to move the switch arm to open and closed positions, a pivoted contact member biased to open position, and current responsive means for releasably restraining said contact member in closed position, said current responsive means being operable in response to overload currents to release the contact member.

7. A circuit breaker comprising a switch member, an operating member movable relative to said switch member for moving said switch member to open and to closed position, a pivoted contact member movable relative to said switch member to open and closed position, means biasing the switch member to closed position at all times, electroresponsive means for releasably restraining the contact member in closed position and operable in response to predetermined circuit conditions to release said contact member, and spring means to move the contact member to open position.

8. A circuit breaker comprising a switch member biased to a closed position and movable to an open position, an operating member biased to a closed position and movable to an open position to cause movement of said switch member to open position, a releasable contact member movable to an open position relative to the switch member, a thermal element operable when heated a predetermined amount to release said contact member, and spring means for moving the contact member to open position.

9. A circuit breaker comprising a pivoted switch member, an operating member for moving said switch member to open position, biasing means connecting the switch member and said operating member biasing both of said members to closed position, said biasing means acting to move both of said members to closed position from an open position, a pivoted contact member, current responsive means for releasably restraining the contact member in cooperative relation with the switch member in the closed position, said current responsive means being operable in response to overload currents to release the contact member, and spring means to move the contact member to open position.

10. A circuit breaker comprising a contact member having a normally closed position, an operating member for manually moving said contact member to open position, means biasing the contact member and said operating member to closed position, said biasing means being effective upon release of the operating member to move both of said members to their closed positions, a second contact member engageable by said first mentioned contact member in the closed position thereof, said second contact member being biased to open position away from said first

contact member, and a thermal element for releasably restraining said second contact member in closed position and operable when heated a predetermined amount to release said second contact member.

11. A circuit breaker comprising a pivoted switch member movable to an open position and to a closed position, an operating member for said switch member, said operating member being pivoted independently of said switch member, means comprising an over center spring operatively connecting said switch member and said operating member and acting upon movement of the operating member to open or closed position to move the switch member to open and closed positions with a snap action, a contact member cooperating with the switch member in closed position, and electroresponsive means operable in response to predetermined circuit conditions to cause movement of the contact member to open position.

12. A circuit breaker comprising a switch member movable to an open position and to a closed position, operating mechanism for said switch member comprising an operating member and a spring intermediate said operating member and said switch member, said spring being adjustable to cause automatic movement of the switch member to open position or to closed position according to the adjustment of said spring, a contact member biased to an open position and cooperating with the switch member in closed position, and a thermal element operable when heated a predetermined amount to cause movement of the contact member to open position.

13. A circuit breaker comprising a switch member movable to an open position and to a closed position, operating mechanism for said switch member comprising an operating member movable to open and closed positions and a spring intermediate the switch member and the operating member and operable by said operating member to move the switch member to open position, said spring acting to move the switch member and the operating member to the closed position upon release of the operating member, a contact member having a closed position in which it is engageable by the switch member in the closed position of said switch member, said contact member being biased to open position, and current responsive means operable in response to predetermined circuit conditions to cause movement of the contact member to open position.

14. A circuit breaker comprising a pair of pivoted contact members movable in opposite directions to open and close the circuit, means biasing one of said contact members in opening direction, operating means including an overcenter spring biasing the other contact member closed and operable to cause opening movement of said other contact member with a snap action, and trip means operable in response to overload currents to cause opening movement of said one contact member.

15. A circuit breaker comprising a pair of contact members movable in opposite directions to close and open the circuit, means biasing one of said contact members in opening direction, operating means including a spring biasing the other contact member open and operable to cause closing movement of said other contact member with a snap action, and electroresponsive means operable in response to overload currents to cause

opening movement of said one contact member without displacing the operating means.

16. A circuit breaker comprising a pair of contact members movable in opposite directions to cause opening and closing of the circuit, operating means including an overcenter spring operable to cause movement of one of said contact members to open and to close the circuit with a snap action, means biasing the other contact member in opening direction, and current responsive means operable in response to predetermined circuit conditions to cause movement of said other contact member to open the circuit.

17. A circuit breaker comprising a switch member, operating means for said switch member comprising an operating handle movable to an open position and to a closed position, and an overcenter spring operable to move the switch member to an open position and to a closed position, means for adjustably connecting said spring to one point of the switch member to cause automatic movement of the switch member to the open position when the handle is released in the closed position and to another point of said switch member to cause automatic movement of the switch member to closed position when the handle is released in the open position, a contact member cooperating with the switch member in the closed position and operable to an open position, and current responsive means operable in response to overload currents to cause operation of said contact member to open position.

18. A circuit breaker comprising a switch member, operating means for said switch member comprising an operating handle movable to an open

- position and to a closed position and an overcenter spring connected to said switch member and operable to move the switch member to an open position and to a closed position, means for adjusting the connection of said spring to the switch member to cause automatic movement of said switch member to open position when the handle is released in closed position, and for adjusting said connection to cause automatic movement of the switch member to the closed position when the handle is released in open position, a contact member cooperating with the switch member in closed position and operable to an open position, and a bimetal element operable when heated a predetermined amount to cause operation of the contact member to the open position.
19. A circuit breaker comprising a switch member, operating means comprising an operating member movable to an open and to a closed position, and spring means operatively connecting the switch member and the operating member to cause movement of said switch member to an open position and to a closed position, a contact member cooperating with said switch member in a closed position and biased open, and a thermal element for releasably restraining said contact member in closed position, said thermal element being operable when heated a predetermined amount to release the contact member, said operating member remaining in closed position following release of said contact member, and said operating member being operable to reset said contact member when said operating member is manually moved to open position.

HAROLD G. BAXTER.
